[57] CLAIM

The ornamental design for a laser smoke particulate/odor filter unit for use in surgical environments, as shown and described.

DESCRIPTION

FIG. 1 is a perspective view of a laser smoke particulate/odor filter unit for use in surgical environments showing the new design;

FIG. 2 is a top plan view;

FIG. 3 is a bottom plan view;

FIG. 4 is a front elevational view, the rear being substantially a mirror image thereof.

Fig. 1.

Fig. 2.

Fig. 4.

Fig. 3.
